UNITED STATES PATENT OFFICE.

ARTHUR S. HICKLEY, OF MANASQUAN, NEW JERSEY.

ELECTROLYTIC ALTERNATING-CURRENT RECTIFIER.

No. 900,278.

Specification of Letters Patent.

Patented Oct. 6, 1908.

Application filed November 12, 1907. Serial No. 401,835.

To all whom it may concern:

Be it known that I, ARTHUR S. HICKLEY, a subject of the King of Great Britain, residing at Manasquan, in the county of Monmouth and State of New Jersey, have invented certain new and useful Improvements in Electrolytic Alternating-Current Rectifiers; and I do hereby declare the following to be a full, clear, and exact description of 10 the invention, such as will enable others skilled in the art to which it appertains to make and use the same.

My invention relates primarily to electrolytic alternating-current rectifiers, is especially adapted for currents of high tension, has for its object the prevention of short circuiting or jumping of the current from one electrode to the other, the prevention of 15 oxides and precipitates forming in the cell 20 and lowering the freezing point of the electrolyte, and the prevention of excessive heating of the electrolyte; and consists in certain improvements, which will be fully disclosed in the following specification and claims.

25 In the practical operation of alternating-current rectifiers of the class described, it has been found that after working, that is passing electricity through an electrolytic cell, transformer or rectifier, one electrode which 30 is aluminum and the other iron or carbon or other suitable material, that the electrolyte composed of phosphate of soda, carbonate of soda or other chemical solution, has its temperature raised to such a degree that its efficiency is greatly impaired, and the current 35 instead of traveling down through the electrolyte from one electrode to the other, crosses the cell, short circuits both impulses, or jumps from one electrode to the other in 40 the most direct route. It is my purpose to remedy these defects in the manner herein-after described.

In the accompanying drawings, which 45 form part of this specification:—Figure 1 represents a vertical section of an electrolytic-current rectifier embodying my invention. Fig. 2 a like view of a modified form of construction. Fig. 3 a vertical section of another modification of the device, on a reduced scale, and Fig. 4 a perspective of the 50 cell shown in Fig. 2, detached.

Reference being had to the drawings and the designating characters thereon, the numeral 1 indicates a tank or receptacle, made 55 of metal or other preferred material, and which forms one electrode of the cell. 2 a

cell also preferably made of metal. The tank 1 contains a body 3, preferably of oil, glycerin or other high non-conducting material, to which the cell 2 is exposed. The 6 body 3 may be in liquid or semi-liquid form, and the cell 2 may be cylindrical, or in any preferred form, and contains a suitable electrolyte 4.

Within the cell 2 are arranged cells 5, 6, 61 which constitute partitions for separating the electrolyte and forming passages 7, 8, 9, between the wall of the cell 2 and the electrode 10 through which the current travels from one electrode to the other. These cells 76 5, 6, are preferably made of porcelain or other suitable material, and in the wall of the cell 5, are openings 11, and in the wall of the cell 6, are openings 12, to provide for the circulation of the electrolyte and the 75 passage of the current. These openings 11, 12 are preferably arranged at or near the opposite ends of the cells, to lengthen the path or route through which the current must travel from one electrode to the other, and 80 thus reduce the possibility of the current short circuiting or jumping.

The electrodes are provided with binding posts 13 and 14 respectively, and within the upper end of the cell 2, is a body 15 of suitable insulating material to prevent the current passing to the wall of the cell 2, except 85 where desired.

The electrode 10 is enlarged at its lower end 16, and the reduced portion 17 thereof 90 is provided with a cover 18 of suitable non-conducting material, and the electrode is extended well down into the electrolyte to prevent undue heating of the electrolyte on its surface or in the upper part of the cell. 95 This undue heating of the electrolyte due to the usual construction of the electrode, not infrequently causes the electrolyte to become more highly heated on the surface than in the body thereof.

100 The walls of the cells 5, 6, may be extended above and beyond the upper end of the cell 2 to prevent short circuiting or jumping of the current from one pole to the other, and the cells may be closed or covered at their 105 upper end and sealed if desired, for the same purpose and for protection.

In the construction shown in Figs. 2 and 4, the end wall 19 is reduced in height so that it does not extend to the surface of the electrolyte and partitions or walls 20, 21 are interposed between the wall 19 and the elec- 110

trode 10, so that the current must travel from the electrode 2 up the passage 22, over the wall 19, down passage 23, through the opening 24 under the partition 20, up the passage 25, over the partition 21 and into the electrolyte surrounding the electrode 10. The partition 20 and the wall 26, may be extended above the cell to prevent short circuiting or jumping of the current, as in the former construction.

In the construction shown in Fig. 3, a cell 27 of suitable porous material is placed in the cell 2 and the current required to pass through the porous wall of the cell 27 in its travel from one electrode 28 to the other electrode 10. Part only of the wall 27 may be porous.

In each of the constructions shown, the current is obstructed in its passage from one electrode to the other, or the path or circuit lengthened beyond what it would be were the current permitted to travel directly from one pole to the other, and the possibility of short circuiting or jumping of the current reduced to the minimum. The heat developed or generated in the electrolyte is taken up or imparted to the body in the tank and radiated through the wall of the tank.

It is obvious that changes in the form and details of construction may be made without departing from the spirit of my invention.

The electrolyte composed of a solution of phosphate of soda, phosphate of ammonium, carbonate of soda and like chemicals and

water, allows oxids and precipitates to form 35 and collect in the cell, which tends to impair the action of the electrolyte and also to short circuit the electrodes. To overcome this serious defect, as far as it is possible, and to lower the freezing point of the electrolyte, I 40 add glycerin in proportions according to the varying work required and the low degrees of temperature to which the electrolyte is exposed. I usually use water and glycerin, in equal parts, but the proportion of glycerin may be varied as from practically all glycerin to a very small percentage thereof.

Having thus fully described my invention, what I claim is—

1. An electrolytic alternating-current rectifier having insulating members extending into the electrolyte and above the cell for protecting the terminals against short circuiting.

2. In an electrolytic alternating-current rectifier, an electrolyte containing a substance for preventing oxids and precipitates forming and collecting in the cell.

3. In an electrolytic alternating-current rectifier, an electrolyte containing glycerin for preventing oxids and precipitates forming and collecting in the cell.

In testimony whereof I affix my signature, in presence of two witnesses.

ARTHUR S. HICKLEY.
